UNITED STATES PATENT OFFICE

2,619,823

WATER CONTROL SYSTEM FOR AUTOMATIC
WASHERS AND THE LIKE

John H. Palmer, Milford, Conn., assignor to General Electric Company, a corporation of New York

Application November 24, 1950, Serial No. 197,385

2 Claims. (Cl. 68—12)

1

My invention relates to control systems and, more particularly, to water control systems for automatic clothes washing machines and the like.

In automatic clothes washing machines, it is not only necessary to open and close the water valves at the proper time in accordance with a predetermined time cycle, but it is also necessary that the water valves be operated at the proper time with respect to the desired condition of the clothes being washed. That is, agitation of the clothes should not begin until the basket has been filled with water. After the basket has been filled, it is desired that agitation proceed uninterrupted for the predetermined length of time. Next, the water should be emptied from the basket and the clothes partially dried by centrifugal extraction while the water is pumped out of the washing machine and the control system reset for the next operation in the time cycle. Mechanisms to perform the above operations are already in existence. However, they generally employ separate motors for drive and for pumping.

Therefore, an important object of my invention is to provide an improved water control system for automatic clothes washing machines and the like having the pump coupled to the drive motor. Another object of my invention is to provide an improved water control system for automatic clothes washing machines and the like in which the water pump operates continuously while the washing machine is in operation.

In carrying out my invention in the preferred form thereof, the water pump, provided for emptying the washing machine, is mounted on the drive unit so that the pump operates all the time that the washing machine is running. The washing machine is also provided with a catch basin, a float switch, and a siphon mechanism, all of which cooperate to control the valve supplying water to the washing machine at the proper time for the program desired for washing the clothes.

For additional objects and advantages and for a better understanding of my invention, attention is now directed to the following description and the accompanying drawing and also to the appended claims in which the features of my invention believed to be novel are particularly pointed out. Fig. 1 is a sectional view in elevation of an automatic washing machine embodying my invention; Fig. 2 is a schematic diagram of the control circuit for an automatic washing machine embodying my invention; and

2

Fig. 3 is a sectional view in elevation of a portion of an automatic clothes washing machine embodying a modification of my invention.

Referring to the drawings, the basket 1 is mounted for rotation within the automatic washing machine 2. The agitator 3 is rotatably mounted in basket 1. The shaft 4 is secured to agitator 3 and is driven in continuous rotation or in oscillatory rotation by the electric motor 5. Motor 5 drives agitator 3 through a drive mechanism 6, such as the fluid operated clutch and brake mechanism disclosed by Thomas T. Woodson in his application, Serial No. 639,817, filed January 8, 1946, issued October 17, 1950 as Patent No. 2,526,444, and assigned to the same assignee as my present invention. The pump 7 is also driven by motor 5.

Agitator 3 is provided with a longitudinal aperture 8 through the length thereof which is connected to the outside of agitator 3 by the ports 9 in the upper portion of agitator 3. Basket 1 is provided with the ports 10 in the upper portion thereof, and with the ports 11 in the bottom thereof. Water is supplied to the washing machine through a solenoid operated valve 18. The lower, or tub, portion 12 of washing machine 2 is provided with an aperture 13 which is connected to the intake side of pump 7 by the tube 14.

The catch basin 15 is annular in shape and is conveniently mounted on drive unit 6. The float 16, disposed in basin 15, operates the switch 17 which controls the solenoid valve 18. The siphon 19, secured to basin 15, is provided to draw water out of basin 15.

Before the washing machine begins to operate, there is no water in basket 1, basin 15, or in tub portion 12. Float 16 rests on the bottom of basin 15. As soon as the washing machine is energized, solenoid valve 18 is energized and water enters basket 1. As soon as basket 1 is nearly full, water overflows through ports 9 into aperture 8 and passes through ports 11 into catch basin 15. As basin 15 is filled, float 16 is raised, and switch 17 is operated. Solenoid valve 18 is de-energized by the operation of switch 17, and the flow of water is cut off.

Switch 17 also has contacts which energize motor 5 as soon as solenoid valve 18 is de-energized. When motor 5 is energized, the agitate cycle begins. As long as motor 5 is operating, pump 7 is also operating and any water slopping out of basket 1 falls into tub portion 12 and is drawn off by pump 7.

When the spin cycle begins, water is thrown out of basket 1 through ports 10 and falls into

tub portion 12. However, aperture 13 is of such magnitude and the capacity of pump 7 is such that pump 7 cannot draw water out of tub portion 12 as fast as it overflows from basket 1. The overflow accumulates in tub portion 12 and remains there until pump 7 can draw it all away.

During the agitate cycle, the short leg 20 of siphon 19 is filled to the level of the water in basin 15. As tub portion 12 begins to fill up with water, the long leg 21 of siphon 19 also begins to fill up with water, thereby compressing the air trapped in siphon 19 and forcing some of the water out of short leg 20. By the time all of the water has been thrown out of basket 1, the level of the water in tub portion 12 is such that all of the water and some of the air has been forced out of leg 20. As pump 7 begins to catch up and the water level in tub portion 12 drops, water is drawn back into short leg 20 from basin 15. As soon as enough water passes from leg 20 to leg 21 so that the column of water in leg 21 is greater than the column of water in leg 20, siphon 19 begins to run freely, and all the water is drawn out of basin 15. It has been found that the long leg 21 should be at least twice as long as short leg 20 in order that enough air may be expelled from short leg 20 to enable the siphon to run freely after the level of the water in tub portion 12 has dropped below basin 15.

Considering now the electric circuit required to supplement the mechanical portion of the water control system hereinbefore described, I refer to Fig. 2. The alternating supply conductors 22 and 23 supply electrical energy to the control circuit for washer 2. A conventional program switching arrangement controls the washing machine operation. The program switch comprises the control motor 24 driving the cams 25, 26, 27, and 28. Each of the cams operates a correspondingly designated switch in the control circuit. The knob 29 is secured to shaft 24a for initiating operation of the washing machine.

Motor 5 is provided with a starting contactor, such as the relay 30, having normally open contacts and responsive to currents above a predetermined level. When motor 5 is energized, relay 30 is picked up by the high starting current and closes the normally open contacts 30a to connect the starting windings of motor 5. As motor 5 comes up to speed the counter E. M. F. produced by the armature of motor 5 reduces the current through the operating coil of relay 30, causing relay 30 to drop out, thereby de-energizing the starting windings of motor 5. The fluid operated clutch and brake mechanism 6 of Fig. 1 is controlled by a solenoid valve having its operating coil 31 connected across supply conductors 22 and 23 through contacts 23b. When solenoid operating coil 31 is energized, the washing machine is shifted to the spin mode of operation.

To energize the washing machine, knob 29 is turned to the start position. This operation opens contacts 27a and 26b and closes contacts 26a and 25a. The solenoid water valve operating coil 18a is energized through the contacts 17a and 26a. Solenoid water valve 18 opens the path for water to flow into the washing machine. When basket 1 is full, water overflows through agitator ports 9 and fills catch basin 15, raising float 16 to close contacts 17b. Switch 17 is provided with snap-action so that contacts 17b are closed as soon as contacts 17a are opened. Closing contacts 17b de-energizes coil 18a and closes valve 18. Drive motor 5 and program control

motor 24 are energized. Relay 30 picks up and motor 5 comes up to operating speed, as hereinbefore described. Control motor 24 is energized through contacts 17b and contacts 28a.

5 The washing machine is now in the washing, or agitate, cycle. Just before the end of the wash cycle, contacts 27a and 28b are closed, thereby connecting the control motor 24 and drive motor 5 across supply conductors 22 and 23 independently of float switch 17. This insures continuous operation of drive motor 5 and control motor 24 during the switch from agitate to spin.

10 After the prescribed period of agitation, cam 26 opens contacts 26a and closes contacts 26b, thereby energizing the solenoid spin valve operating coil 31. When all the water is removed from the washing machine during the spin cycle, as hereinbefore described, float 16 is returned to the bottom of catch basin 15, thereby closing contacts 17a and preparing the washing machine 15 for the next cycle of operation.

20 After the end of the spin cycle, contacts 26b, 27a, and 28b are opened. Contacts 26a and 28a are closed. The washer is filled with water again and an agitate cycle follows for rinsing the clothes, as hereinbefore described for the washing operation. Just before the end of the rinse cycle, contacts 27a are closed. At the end of the rinse cycle, contacts 23b are closed, thereby initiating 25 a second spin cycle. At the end of the second spin cycle, cam 25 opens contacts 25a, thereby de-energizing drive motor 5, control motor 24, and the remainder of the control circuit.

30 In the modification illustrated in Fig. 3, catch basin 15 is replaced by a well 32 in the bottom of tub portion 12. A standpipe 33 connects tub portion 12 with the intake side of pump 7. Siphon 19 extends into standpipe 33 through an aperture in the side thereof so that leg 21 extends down through standpipe 33 and leg 20 extends outside standpipe 33 almost to the bottom of well 32. Float 16 is here mounted in the bottom of tub portion 12.

35 After basket 1 has been filled, water overflows through ports 10 in tub portion 12. The overflow fills well 32 and a portion of tub 12, thereby raising float 16 to operate switch 17. Operation of the washing machine continues as hereinbefore described until the spin cycle starts and basket 1 is emptied. At that time, the water is thrown out of basket 1 through the ports 10, thereby filling tub portion 12.

40 At the beginning of the washing machine cycle, the overflow from basket 1 which operates switch 17 does not fill tub portion 12 to the level BB so that siphon 19 is not effectuated. Thus, float 16 remains in the raised position and the agitate cycle continues uninterrupted until the program mechanism starts the spin cycle, as hereinbefore described. When the water rises above the level BB, siphon 19 begins to run freely but cannot draw enough water to stop the filling of tub portion 12. The water level in tub portion 12 continues to rise and ultimately rises 45 above the level CC. Water now flows through standpipe 33 and is drawn away by pump 7. After basket 1 is emptied and the water level drops below CC, no more water can enter pump 7 through standpipe 33 and siphon 19 completes 50 the task of emptying the tub portion 12. Siphon 19 empties all of tub portion 12 except the residue water below the level AA.

55 Pump 7 operates throughout the entire washing machine cycle. However, since standpipe 33 extends above the water level in tub por-

tion 12 during the entire agitate cycle, pump 7 chooses the lighter work of drawing air through standpipe 33, rather than drawing water from well 32 through siphon 19. Therefore, float 16 is held in the raised position until after the spin cycle has started and tub portion 12 has been drained.

While the present invention has been described by reference to particular embodiments thereof, it will be understood that this is by way of illustration of the principles involved and that those skilled in the art may make many modifications in the arrangement and mode of operation. Therefore, I contemplate by the appended claims to cover any such modifications as fall within the true spirit and scope of this invention.

What I claim as new and desire to secure by Letters Patent of the United States is:

1. In a washing machine having a water-collecting tub and a rotatable clothes basket supported therein, a water control system comprising electro-responsive valve means controlling the supply of water to said basket, an energizing electric circuit for said valve means, switch means controlling said circuit, a water overflow passageway in said basket, means for draining said tub, a catch basin spaced above said tub and supported under said basket overflow passageway to collect water therefrom, float means in said basin adapted to operate said switch means in response to a predetermined water accumulation in said basin, a siphon having a relatively short leg extending into said basin and a relatively long leg at least twice the length of said short leg depending from said basin, and means supplying said tub with water to a level above the lower end of said short leg to condition said siphon for operation whereby said siphon drains said basin upon removal of the water in said tub.

2. In an automatic clothes washing machine having an aperture in the bottom thereof and having an electric drive motor, a water control system comprising a clothes-receiving basket mounted for rotation in said washing machine, an agitator mounted in said basket for rotation about the axis of rotation of said basket,

solenoid-operated valve means for controlling the flow of water into said basket, said agitator having a longitudinal aperture through the center thereof and having ports in the upper portion thereof for admitting water from said basket to said longitudinal aperture, said basket having ports in the central portion of the bottom thereof and having a hub portion connecting said basket ports with the lower end of said longitudinal aperture and sealing both from the remainder of said basket, said basket having overflow ports in the upper portion of the circumference thereof for discharging water contained in said basket in response to the spinning of said basket, a pump mounted to be driven by said motor for removing water accumulated in the bottom of said washing machine, a tube connecting said aperture to said pump, a basin mounted in said washing machine below said basket ports for catching and retaining water spilled from said basket through said agitator ports in response to the filling of said basket, a float disposed in said basin, a switch connected to said float and operated thereby in response to the changing water level in said basin, a siphon having a short leg and a long leg at least twice as long as said short leg for withdrawing water accumulated in said basin, said siphon effectuated in response to the accumulation of water in the bottom of said washing machine forcing air from said short siphon leg thereby enabling said siphon to run freely when said accumulated water is removed, and a circuit for energizing said solenoid-operated valve means, said float switch having contacts in series in said solenoid-operated valve means energizing circuit for de-energizing said solenoid in response to a rising water level in said basin.

JOHN H. PALMER.
